UNITED STATES PATENT OFFICE.

CHARLES J. DAVIDSON AND EUCLID P. WORDEN, OF MILWAUKEE, WISCONSIN, ASSIGNORS TO FRED M. PRESCOTT STEAM PUMP COMPANY, OF WEST ALLIS, WISCONSIN, A CORPORATION OF WISCONSIN.

CONDENSER.

No. 807,251.

Specification of Letters Patent.

Patented Dec. 12, 1905.

Application filed May 11, 1905. Serial No. 260,023.

To all whom it may concern:

Be it known that we, CHARLES J. DAVIDSON and EUCLID P. WORDEN, citizens of the United States, residing at Milwaukee, in the county of Milwaukee and State of Wisconsin, have invented certain new and useful Improvements in Condensers, of which the following is a specification, reference being had to the accompanying drawings, forming a part thereof.

10 This invention relates to jet or injection condensers.

The main objects of the invention are to entrain and discharge with the water the greater portion, if not all, of the air entering 15 the condenser with the injection or cooling water and steam, thereby maintaining the desired vacuum and reducing the required capacity and size of or altogether dispensing with the dry air-pump without materially increasing the supply of injection-water, and 20 generally to improve the construction and operation of condensers of this class.

It consists in certain novel features of construction and in the peculiar arrangement and 25 combinations of parts, as hereinafter particularly described, and defined in the claims.

In the accompanying drawings like characters designate the same parts in the several figures.

30 Figure 1 is a vertical section of one form of condenser embodying our invention. Figs. 2 and 3 are similar views of modified forms of the condenser.

Referring to Fig. 1, the condenser-case *a*, 35 which may be of the usual inverted-pear shape or of any other suitable form, is divided into upper and lower chambers *b* and *c* by a horizontally-disposed conical partition *d*. The exhaust-steam-inlet pipe *e* is attached to the 40 top of the casing and communicates with the upper chamber *b* through a downwardly-directed steam cone or nozzle *f*. The injection or cooling water inlet connection *g* is made through one side of the case and opens into 45 the upper chamber *b* just above the partition *d*. Just below said partition an air-exhaust connection *h* may be provided for withdrawing air, if necessary, from the upper part of the chamber *c*. A water cone or funnel *i* 50 leads from the upper chamber *b* into the lower chamber *c* through the partition *d*, by which it is supported in line with the nozzle *f*, projecting slightly into its upper and larger end.

A contracted throat *j* is centrally supported by a spider or radial wings *k* in the lower end 55 of the case *a* below and in line with the funnel *i*. To the lower end of this throat is attached a barometric or gravity tail-pipe *l*, the lower end of which extends into a water-way or receptacle *m* below the normal liquid-level therein. An outer tail-pipe *n*, surrounding the pipe *l*, is attached at its upper end to the lower end of the case *a* in communication 60 with the chamber *c* and projects at its lower end into the waterway or receptacle *m* below the liquid-level therein. These tail-pipes are made of such a length that the water will not rise between them above the throat *j* by reason of the vacuum produced and maintained in the condenser. To prevent a vertical or 65 whirling movement of the water, which would diminish its velocity and force as it passes through the funnel *i* and throat *j*, the nozzle *f* is preferably provided on the outside with longitudinal guide-vanes *o* and the funnel *i* 70 and throat *j* on the inside with similar guide-vanes *p* and *q*. To reduce the temperature 75 of the air which is separated from the steam and water as they pass through the chamber *c* and which collects in the upper part of said 80 chamber, the partition *d* is preferably provided on its under and outer side with air-cooling vanes *r*, and when a dry air-pump or other means is employed to exhaust from the 85 upper part of said chamber the excess of air which cannot be entrained with the water and discharged from the condenser through the throat and inner tail-pipe a deflector *s* is provided to direct the air as it passes to the exhaust 90 connection *h* against the partition *d* and its cooling-vanes *r*. This deflector is cast with or attached to the case *a* just below the air-exhaust connection *h* and extends downwardly 95 and inwardly toward the partition *d*. To prevent the splashing of water from the mouth of the throat *j* upwardly into the air-space around the funnel *i* and partition *d*, the lower end of said funnel may be surrounded by a deflector *t*, attached either to the funnel, as shown, or to case *a*. Adjacent to the lower 100 end of the funnel *i* the case is provided with glazed sight-openings *u* for observing the operation of the condenser. This form of the apparatus operates as follows: The cool injection-water entering the upper chamber *b* 105 through the connection *g* fills the annular

space between the upper side of the partition d and the outer side of the funnel i and overflows into the upper end of said funnel in a tubular or funnel form stream. The exhaust-
 5 steam entering the condenser through pipe e is discharged downwardly with considerable force from the nozzle f into and through the funnel i , where it comes in contact with and accelerates the flow of the surrounding stream
 10 of cooling-water, which rapidly condenses the greater part of the steam, thereby producing and maintaining a strong vacuum in the exhaust-steam pipe e and in the chamber b . The tubular stream of water, with air and any
 15 uncondensed vapor that may be carried with it, is discharged from the lower end of the funnel i into the upper flaring end or mouth of the throat j , by which it is contracted and its velocity accelerated. Any air or uncondensed vapor which may escape from the water as it issues from the lower end of the funnel i is caught in the chamber c , from which vapor condensed by contact with the walls of
 20 said chamber drains into the outer tail-pipe n ; but the greater part, if not all, of the air and uncondensed vapor is entrained with the accelerated stream of water into the throat j and carried down through the inner tail-pipe l into the waterway or receptacle m at its
 25 lower end, a strong vacuum being thus produced and maintained in said chamber c . Any air and uncondensed vapor which are not thus discharged and disposed of through the throat and tail-pipe are drawn off through
 30 the exhaust connection h from the upper part of the chamber c , being cooled in their passage to said connection by contact with the partition d and its vanes r , which are kept cool by the injection-water in contact with
 35 the upper and inner side of said partition. In case of any interruption in the flow of water through the throat j and inner tail-pipe l or any increase in the volume of the injection-water which cannot be taken care of in this
 40 way the excess will overflow the upper end of the throat j into the outer tail-pipe n and escape from its lower end into the waterway or receptacle m .

In certain places and under certain conditions barometric or gravity tail-pipes may be dispensed with and a pump connected with the throat and case to dispose of the water, air, and uncondensed vapor discharged from the condenser where an open waterway or receptacle is not available.

Instead of continuing both tail-pipes downward into the waterway or receptacle one of them may terminate and discharge into the other at a point above the normal liquid-level in
 45 the waterway or receptacle, as shown in Fig. 2, in which the inner tail-pipe l' opens into the outer tail-pipe n' above the waterway or receptacle m , but below the level which the water will normally assume in the outer tail-pipe
 50 on account of the vacuum in the condenser

under normal working conditions, and the outer tail-pipe is reduced in size below the inner pipe. In other respects the apparatus shown in Fig. 2 is in construction and operation substantially like that shown in Fig. 1
 70 and hereinbefore described.

Referring to Fig. 3, illustrating other modifications in the construction and arrangement of parts of the condenser, the partition or wall d' , which forms an annular waterway extending around and above the top of funnel i , does not completely divide the case a into separate chambers, but there is free communication outside of said partition between the upper and lower parts of the space enclosed by said case. The lower end of the case is closed around the throat j , and it is provided at one side with a separate connection v for the attachment of the overflow tail-pipe n'' , which takes the place of the outer pipe n of Fig. 1 and is separate from the pipe l . It is obvious that instead of running both of the tail-pipes l and n'' down into the waterway or receptacle m either one of them may be run into the other above said waterway or
 80 receptacle, provided the single pipe below their junction is made of sufficient size to take care of both the main discharge and any possible overflow. The operation of this form of the condenser is essentially like that of the 90 forms shown in Figs. 1 and 2.

Various changes other than those above pointed out in the details of construction and in the arrangement of parts of the apparatus may be made without affecting its principle 100 and mode of operation and within the spirit and intended scope of the invention.

We claim—

1. In a condenser, the combination of a steam-and-water-combining funnel, a case inclosing said funnel and having steam and water inlet connections in constant open communication with the upper end of the funnel and a contracted throat located below, in line with and at a distance from said funnel, an outlet connection with the lower part of the throat, and an overflow-outlet in constant open communication with the space between said funnel and throat, substantially as described.

2. In a condenser the combination of a water cone or funnel, a case inclosing said funnel and having steam and water inlet connections in communication with the upper end of the funnel, an exhaust connection opening out of the air-space between the case and funnel and a contracted throat located below and in line with said funnel and having an outlet connection at its lower end, substantially as described.

3. In a condenser the combination of a water cone or funnel, a case inclosing said funnel and having steam and water inlet connections in communication with the upper end of the funnel and a barometric overflow connection communicating with the lower end of the fun- 130

- nel, and a contracted throat located below, in line with and at a distance from the funnel and having an outlet connection at its lower end, substantially as described.
- 5 4. In a condenser the combination of a water cone or funnel, a case inclosing said funnel and having steam and water inlet connections in communication with the upper end of the funnel, a contracted throat located below, in line with and at a distance from said funnel, and being of smaller area than the funnel; and barometric outlet connections communicating with the upper and lower ends of said throat, substantially as described.
- 15 5. In a condenser the combination of a water cone or funnel, a case inclosing said funnel and having steam and water inlet connections in communication with the upper end of the funnel and an exhaust connection with the air-space around the funnel, a contracted throat located below, in line with and at a distance from the funnel, and barometric outlet-pipes communicating with the upper and lower ends of the throat, substantially as described.
- 25 6. In a condenser the combination of a funnel, a case inclosing said funnel and having steam and water inlet connections in communication with the upper end of the funnel, a contracted throat below and in line with the funnel, and barometric or gravity tail-pipes arranged one within the other and connected with the throat and case respectively, substantially as described.
- 35 7. In a condenser the combination of a funnel, a case inclosing said funnel and having steam and water inlet connections in communication with the upper end of the funnel, a partition or wall surrounding said funnel and provided on the outer or under side with air-cooling vanes, a contracted throat located below and in line with said funnel and having an outlet connection at its lower end, and an exhaust-air connection opening out of said case adjacent to said partition, substantially as described.
- 45 8. In a condenser the combination of a funnel, a case inclosing said funnel and having steam and water inlet connections in communication with the upper end of the funnel, a partition or wall forming a waterway around said funnel and provided with air-cooling vanes on its outer or under side, a deflector extending inwardly from the case toward said partition, an exhaust-air connection opening out of the case above said deflector, and a contracted throat located below and in line with said funnel and having an outlet connection at its lower end, substantially as described.
- 55 9. In a condenser the combination of a funnel, a case inclosing said funnel and having steam and water inlet connections in communication with the upper end of said funnel, a contracted throat located below and in line with said funnel and having an outlet connection at its lower end, and a deflector surround-

ing the lower end of the funnel, substantially as described.

10. In a condenser the combination of a case having steam and water inlet connections in constant open communication with the upper part and an outlet connection with the lower part thereof, the steam-inlet terminating in a downwardly-directed nozzle, a contracted throat located below and in line with said nozzle and communicating at its lower end with said outlet connection, a funnel arranged between, in line with and at a distance from said nozzle and throat, and an overflow outlet connection with the case in constant open communication with the space between the funnel and throat, substantially as described.

11. In a condenser the combination of a case having steam and water inlet connections with the upper part and an outlet connection with the lower part and divided between its inlet and outlet connections into an upper water-chamber and a lower air-chamber, the steam-inlet terminating in a downwardly-directed nozzle, a contracted throat communicating at its upper end with the air-chamber and at its lower end with the outlet connection which is of larger area than the throat, and a funnel of larger area than the throat arranged between and in line with said nozzle and throat and communicating at its upper end with the water-chamber and at its lower end with the air-chamber, substantially as described.

12. In a condenser the combination of a case divided into upper and lower chambers and having steam and water inlet connections opening into the upper chamber, a funnel leading from the upper into the lower chamber, a contracted throat located below and in line with said funnel and communicating at its upper end with the lower chamber, and tail-pipes connected with the lower chamber and said throat, substantially as described.

13. In a condenser the combination of a case divided into upper and lower chambers and having steam and water inlet connections opening into the upper chamber, a funnel between said chambers, a contracted throat located below and in line with said funnel and communicating at its upper end with the lower chamber, and tail-pipes arranged one within the other and connected with said throat and the lower chamber, substantially as described.

14. In a condenser the combination of a case having steam and water inlet connections, a funnel inclosed in said case, a contracted throat below and in line with said funnel, and gravity tail-pipes connected at their upper ends with said throat and case and extending at their lower ends into a waterway or receptacle below the normal liquid-level therein, substantially as described.

15. In a condenser the combination of a funnel having on the inside longitudinal guide-vanes, and a case inclosing said funnel and having steam and water inlet connections in com-

munication with the upper end of the funnel, and a contracted throat below the funnel, substantially as described.

16. In a condenser the combination of a funnel, and a case inclosing said funnel and having steam and water inlet connections in communication with the upper end of the funnel and a contracted throat below the funnel, the steam-inlet connection terminating within the upper end of the funnel in a downwardly-directed nozzle which has longitudinal guide-vanes on the outside, substantially as described.

17. In a condenser the combination of a funnel having on the inside longitudinal guide-vanes, a case inclosing said funnel and having steam and water inlet connections communicating with the upper end of the funnel and an outlet connection communicating with the lower end of the funnel, and a nozzle projecting from the steam-inlet connection into the upper end of the funnel and having longitudinal guide-vanes on the outside, substantially as described.

18. In a condenser the combination of a funnel, a case inclosing said funnel and having steam and water inlet connections communicating with the upper end of the funnel, a throat located below and in line with said funnel and having on the inside longitudinal guide-vanes, and a tail-pipe connected with the lower end of said throat, substantially as described.

19. In a condenser the combination of a case having steam and water inlet connections, the steam-inlet terminating in a downwardly-directed nozzle which has on the outside longitudinal guide-vanes, a funnel inclosed by said case in line with said nozzle and having on the inside longitudinal guide-vanes, a throat located below and in line with said funnel and having on the inside longitudinal guide-vanes, and an outlet connected with the lower end of said throat, substantially as described.

20. In a condenser the combination of a case divided into upper and lower chambers and having steam and water inlet connections opening into the upper chamber and an air-exhaust connection leading out of the upper part of the lower chamber, a funnel leading from the upper into the lower chamber, a throat located below and in line with said funnel and a tail-pipe connected with the lower end of the throat, substantially as described.

21. In a condenser the combination of a case divided by a partition into upper and lower chambers and having steam and water inlet connections opening into the upper chamber,

a funnel leading from a point in the upper chamber above said partition into the lower chamber which has an air-exhaust connection 60 leading out from the upper part thereof, a throat located below and in line with said funnel and a tail-pipe connected with the lower end of the throat, said partition being provided on the under side with air-cooling vanes, 65 substantially as described.

22. In a condenser the combination of a case divided into upper and lower chambers by a horizontally-disposed conical partition and having steam and water inlet connections with 70 the top and side respectively of the upper chamber, and an air-exhaust connection leading out from the upper part of the lower chamber, the steam-inlet terminating in a downwardly-directed nozzle, a funnel passing 75 through said partition in line with said nozzle, a throat located below and in line with said funnel and a tail-pipe connected with the lower end of said throat, substantially as described.

23. In a condenser the combination of a case divided into two chambers by a horizontally-disposed partition which is provided on the under side with air-cooling vanes and having steam and water inlet connections opening into 85 the upper chamber and an air-exhaust connection opening out of the lower chamber, a funnel leading from the upper into the lower chamber through said partition, a throat located below and in line with said funnel, and a tail-pipe connected with the lower end of said throat, substantially as described.

24. In a condenser the combination of a case divided into upper and lower chambers by a horizontally-disposed partition which is provided on the under side with air-cooling vanes, and having steam and water inlet connections opening into the upper chamber and an air-exhaust connection opening out of the lower chamber, a deflector extending inwardly from 95 the case toward said partition below the air-exhaust connection, a funnel extending through said partition from the upper into the lower chamber, a contracted throat located below said funnel, and a tail-pipe connected with the 100 lower end of said throat, substantially as described.

In witness whereof we hereto affix our signatures in presence of two witnesses.
